UNITED STATES PATENT OFFICE.

FRANK F. AMBROSE, OF LOS ANGELES, CALIFORNIA, ASSIGNOR TO UNION STEAM PUMP COMPANY, OF BATTLE CREEK, MICHIGAN, A CORPORATION.

ROTARY PUMP.

1,390,744.

Specification of Letters Patent. Patented Sept. 13, 1921.

Application filed February 24, 1919. Serial No. 278,726.

To all whom it may concern:

Be it known that I, FRANK F. AMBROSE, a citizen of the United States, residing at the city of Los Angeles, county of Los Angeles, 5 State of Cal., have invented new and useful Improvements in Rotary Pumps, of which the following is a specification.

My invention relates to that class of rotary pumps in which pistons are operated 10 by a rotor in which they reciprocate; and the objects thereof are to prevent wear on the interior of the pump chamber casing and on the edges of the piston blades. A further object is to construct a pump of 15 few parts in which the internal parts can be inspected or moved easily. A further object is to dispense with cams to cause the reciprocation of the piston blades.

In the drawings forming part of this application Figure 1 is a vertical cross section 20 of the preferred form of pump on the line 1-1 of Fig. 2.

Fig. 2 is a longitudinal section on the line 2-2 of Fig. 1. Fig. 3 is an end view of a 25 piston. Fig. 4 is an edge view of a four blade piston detached. Fig. 5 is an edge view of one of the piston blades shown in edge view in Fig. 4. Fig. 1^a is a vertical longitudinal section of a modified form 30 of pump on the line 1^a-1^a of Fig. 2^a. Fig. 2^a is a cross section on the line 2^a-2^a of Fig 1^a. Fig. 3^a is a cross section on the line 3^a-3^a of Fig. 1^a with the case omitted. Fig. 4^a is a perspective view of the piston of 35 Fig. 1^a. Fig. 5^a is a perspective view of a wearing plate.

In the drawings 10 is the base plate which is secured to the floor 11 of the place of use. The body 12 of the pump chamber 40 casing has legs 13 which are bolted to plate 10. Head 14 is removably secured to the body by bolts 15 so that by removing them the head can be taken off and the working parts removed for repairs or replacement. 45 Head 16 is preferably cast integral with the body and is provided with a boss 17 which is eccentric to the center of the head. This boss is centrally bored to receive shaft 21. Rotor 19 is eccentrically mounted in chamber 20 and is secured to and rotates with 50 said shaft. Shaft 21 is revolvably mounted in standards 22 secured to plate 10 and suitable power is applied to rotate the same when the pump is operated. The outer shell 55 of rotor 19 extends through the length of

chamber 20 and has equidistant slots 24, 25, 26 and 27 therein in which are received piston blades 28, 29, 30 and 31. At the sides of these slots are stiffening ribs 32. Blades 28 and 29 are connected by hollow hub 33 60 and with said hub form a piston. Blades 30 and 31 are connected by a like hub 34 and form a piston. It will be observed that hub 34 is at one end of the blades and hub 33 lies just within hub 34 when the pistons are 65 assembled and the blades attached to hub 34 are notched for the reception of hub 33, and the blades attached to hub 33 are notched at the ends for the reception of hub 34. The other ends of the blades are also notched. 70 Within hubs 33 and 34 the blades of both pistons are provided with guide lugs 28^a, 29^a, 30^a and 31^a and the faces of the opposed lugs lie in parallel planes and are provided with wearing plates 37. I have shown the 75 blades and hubs and lugs integral but it is obvious they could be formed separately. Head 14 is bored concentrically for the reception of guide stub shaft 35 which extends to shaft 21. Within the lugs of the 80 blades of the pistons is a guide block 36 revolvably mounted on shaft 35, which guides the pistons when the pump is being operated and prevents the edges of the blades from contacting with body 12. Block 36 and 85 plates 37 can be tempered and removed and replaced when worn. In the outer end of shaft 35 I provide a grease cup 38 from which channel 39 extends to its connection with cross channels 40. Channels 40 terminate in an annular groove 49 in block 36. 90 From groove 49 channels 41 extend to each plate 37 to lubricate the same. While I have shown the shell of the rotor connected to the hub thereof at one end of the pumping chamber it is obvious that such connection could be made nearer the center and in engagement with the guide lugs. In such case the blades of the pistons would not be notched at that end. Body 12 is provided 95 with inlet port 42 and outlet port 43.

In my modified form I use only one pair of blades, 44 and 45 which are connected by a box shaped hub 46 and form the piston. I prefer to use guide blocks 47 and 48 at 100 the ends of the hubs, but could use one block in the center and use lugs on the blades and another form of hollow hub.

By this construction it will be seen that I have reduced the number of parts usual 110

in rotary pumps and have dispensed with the usual cams which cause the reciprocation of the blades of this class of pumps.

Having described my invention I claim—

- 5 1. In a rotary pump of the class described, a casing having an annular pumping chamber therein provided with inlet and outlet ports; a driven shaft eccentrically mounted in one of the heads of said chamber; a rotor 10 in said chamber secured to said shaft, said rotor having slots therein; a plurality of pistons in said chamber, each piston comprising a pair of blades connected by a hollow hub and mounted to have the blades 15 reciprocate in the slots of the rotor; a guide shaft mounted in the other head of said casing concentrically thereto; lugs secured to said blades with their opposed faces parallel; and a guide block revolvably mounted on said guide shaft in engagement with said lugs to guide said pistons and prevent the edges of the blades from contacting with the casing, said guide block contacting with said blades at the centers of said blades.
- 20 2. In a pump of the class described, a casing having an annular pumping chamber therein provided with an inlet and an outlet port; a driven shaft eccentrically mounted in one of the heads of said casing; a 25 rotor in said chamber secured to said shaft, said rotor having slots therein; a piston comprising a pair of blades connected by a hollow hub mounted to have the blades reciprocated in said slots; a guide shaft 30 concentrically mounted in the other head of said casing and extending into said chamber; and a guide block revolvably mounted on said guide shaft to guide said piston

and prevent the edges of the blades from contacting with said casing, said guide block contacting with said blades at the centers of said blades.

3. In a rotary pump of the class described a casing having an inlet and an outlet port; a piston having a box-shaped hub in said casing; a rotor to operate said piston; means to operate said rotor; a guide block to guide said piston; and a shaft to position said block, said last shaft being concentric and the rotor shaft being eccentric to the casing heads, said block being square and revolvably mounted on said shaft.

4. In a pump of the class described, a casing having an annular pumping chamber provided with an inlet and an outlet port; a driven shaft eccentrically mounted in one of the casing heads and extending to near the center of the pumping chamber; a rotor in said chamber secured to said shaft and contacting with the perimeter of said chamber casing between said ports, said rotor having radial slots therein; a piston comprising a pair of blades connected by a hub having an opening at the center; a guide shaft concentrically mounted in the other head of said casing and extending to the driven shaft; a square guide block concentrically and revolvably mounted on said guide shaft at the center of the pumping chamber and adapted to contact with the inner edges 70 of said blades and guide them as the rotor is revolved.

In witness that I claim the foregoing I have hereunto subscribed my name this 28th day of January 1919.

FRANK F. AMBROSE.
